UNITED STATES PATENT OFFICE.

HARRY B. ARNOLD, OF NEW BRITAIN, CONNECTICUT, ASSIGNOR TO THE NATIONAL SPRING BED COMPANY, OF NEW BRITAIN, CONNECTICUT, A CORPORATION OF CONNECTICUT.

COUCH-BED.

Specification of Letters Patent. Patented Mar. 6, 1917.

1,218,608.

Application filed January 14, 1914. Serial No. 812,030.

To all whom it may concern:

Be it known that I, HARRY B. ARNOLD, a citizen of the United States, and a resident of New Britain, in the county of Hartford and State of Connecticut, have invented a new and Improved Couch-Bed, of which the following is a specification.

My invention relates more especially to that class of devices which may be used for couch purposes, and which may be unfolded to serve as a bed, and an object of my invention, among others, is to provide a device of this class that shall be extremely simple in its construction, that shall be practically effective for the purpose for which it is constructed, and one that may be easily operated.

One form of couch embodying my invention, and in the construction and use of which the objects herein set out, as well as others, may be attained, is illustrated in the accompanying drawings, in which—

Figure 1 is a view in end elevation of a couch embodying my invention, the parts being shown in their folded condition.

Fig. 2 is a like view showing the parts extended or unfolded, the mattresses being omitted.

Fig. 3 is a view in elevation of the couch looking from the back toward the front, the parts being in their unfolded condition.

Fig. 4 is a plan view of a portion of the couch showing the parts in their unfolded position.

The couch bed herein illustrated and described, and embodying my invention, has two end members or frames, each being of an inverted U-shaped form, the branches of which constitute front legs 6, and back legs 7, the connecting part constituting a cross bar 8. The back legs 7 have a frame rod 9 secured to them, preferably at some distance from their lower ends, and the front legs 6, are rigidly supported as by a frame bar 10, preferably of angular construction, which frame bar is secured at each of its ends to a post 11, each of said posts being rigidly secured to a bracket 12, each of which brackets is rigidly secured to one of the front legs 6. The end members, frame rod, frame bar, strut ends and brackets constitute the main or supporting frame of the couch.

A folding frame, supported upon the main frame, consists of a body or back portion, an extensible portion, and a connecting portion.

The body or back portion is composed of end bars 13, connected at their back ends by a head bar 14, and a wire fabric 15 secured to the end bars. The connecting or rocking portion is composed of link bars 16 at the 60 ends of the portion, pivotally connected at their back ends with the end bars 13, and to which link bars the fabric 15 is secured. The link bars 16 are pivotally supported at the upper ends of the posts 11, upon which 65 posts the link bars have a rocking movement. Studs 30 project from the sides of the link bars near one end and edge as shown in dotted lines in Figs. 1 and 2.

The extensible portion of the folding 70 frame is composed of end bars 17 pivotally connected at their back ends to the link bars 16 and supporting a wire fabric 18, the back edge of this wire fabric 18 extending for a considerable distance, when the supporting 75 frame is unfolded, beyond the front edge of the fabric 15, so that the two fabrics overlap one another. A foot rail 19 rigidly connects the end bars 17 and folding legs 20 are pivotally secured to the end bars 17 near their 80 outer or front ends, all of these parts composing the extensible portion of the structure.

A leg operating rod 21 is pivotally connected to each of the legs 20 and to one of the front legs 6. A locking link connection 22 is pivotally attached to each of the leg operating rods 21 near the connection of the latter with the legs 6, and the opposite end of each locking link connection is slotted to 90 receive a pivot pin from one of a pair of locking links 26. This pivot pin is located near the adjacent ends of each of the pairs of locking links, one member of each pair of said links being pivotally secured to the 95 bracket 12, and an end of the other member of each pair of links being pivotally connected to the link bar 16.

A mattress 23 is secured to the surface of the folding frame, and a cushion 24 is secured to the opposite surface of the extensible portion of the folding frame.

From this construction it will be observed that when the extensible portion of the folding frame is swung upwardly, in the operation of extending this portion of the frame, it will turn upon the pivots at the front or upper ends of the link bars 16 until the weight of this extensible portion is so disposed as to overcome the weight of the body 116

portion when the swinging movement will take place at the pivots at the upper ends of the strut ends 11, a part of this extensible swinging movement, under certain conditions, taking place simultaneously at the pivots at the outer ends of the link bars 16 and at the upper ends of the strut ends 11. This extensible swinging movement disposes the parts in the position shown in Fig. 2, the front end or edge of the body portion of the folding part of the couch being drawn upwardly from the position shown in Fig. 1 and its opposite edge being slid backwardly up the guides or supports 25 secured to the frame rod 9 and supported in inclined position, as shown in Figs. 1 and 2 of the drawing, to receive the head bar 14, each of these guides 25 having an extension from its back end to support the head bar, when the couch is in its unfolded or extended position. As the extensible portion is swung as described, to its extended position, the leg operating rods 21 will act to swing the legs upon their pivots, the ends of the legs first moving away from the end bars 17 and then moving toward said end bars and past them to the position shown in Fig. 2 of the drawing. The locking link connections 22 are pivotally connected to the leg operating rods 21, in such manner that when the couch has been unfolded, the pins upon the locking links connection may operate to draw the locking links into their locked position as the parts are finally opened. As the folding operation takes place, the joint 31 connecting each pair of locking links may be provided with any suitable stop for preventing them from breaking forward. It will be noted that the slots in the locking link connections, permit the extensible portion of the structure to be swung partially to its closed position before the locking links are operated to unlock the parts, this latter operation being effected by the engagement of the ends of the slots with the pivot pins, which engagement moves the locking links to unlock the parts and permits them to be swung to the position shown in Fig. 1. The end bars 17 of the extensible portion swing upon the pivots at the outer or front ends of the link bars 16 in which movement the locking link connections 22 move independently of the locking links 26 by reason of the pin and slot connection. Just before the ends of the slots engage the pins to unlock said link, as above described, the edges of the end bars 17 are moved against the studs 30 and the link bars 16 are thus caused to swing upon their pivots at the ends of the posts 11. When the parts have been swung to their closed positions as shown in Fig. 1 of the drawings, the edges of the end bars 17 resting against the studs 30 (see dotted outlines in Fig. 1 of the drawings) prevents any swinging movement of the link bars 16, such as would cause the

structure to collapse for the reason that the end bars 17 are supported upon the studs 30. In this position it will be noted that the front edge of the body portion of the folding frame is lowered to create a space or cavity 27 between the extensible portion and the body portion, this cavity occurring at the front edge of the latter, the back edge being closed by the meeting surfaces of the folded mattress. This cavity provides a closed receptacle for pillows or like articles. 75

It will be noted that the pivots at the ends of the link connections 22 are so located with respect to the pivotal points of connection of the rods to the legs 6 that the parts will be locked against closing movement when the structure is unfolded. Projections 28 from the ends of the foot rail 19 are located to rest upon the cross bars 8, when the parts are in their closed position, and this forms a support or rest for the folding frame. 80

The description and drawing herein discloses my invention as embodied in an approved structure, but this may be departed from to a greater or lesser degree and yet 90 be within the spirit and intent of the invention.

I claim—

1. A supporting frame and a folding frame, the latter including a body portion, an extensible portion, and a pivotally supported rocking portion, and a pivot for said rocking portion located inside of the supporting frame at a distance therefrom to receive the support of the folding frame and 100 prevent collapse of the folding frame by weight thereon.

2. A supporting frame and a folding frame, the latter including a body portion, an extensible portion, and a rocking portion, a post to support said rocking portion, said post being located inside of said supporting frame in a direction crosswise thereof and spaced from the support of said supporting frame a distance to prevent collapse of the folding frame from weight thereon, and means to pivotally connect the portions of said folding frame. 105

3. A supporting frame and a folding frame, the latter including a body portion, an extensible portion, and a rocking portion all pivotally united, a bracket extending inwardly in a direction crosswise of the supporting frame from the side supports of said supporting frame at each end thereof, and posts rising from each of said brackets to support the rocking portion of the folding frame, said posts being spaced from the side supports of the supporting frame in a direction crosswise of the latter a distance sufficient to prevent collapse of the folding frame from a weight placed upon it. 115

4. A main frame and a folding frame supported thereby, said folding frame including a pivotally mounted connecting portion, 120

130

5 a body portion pivotally attached thereto, an extensible portion also pivotally attached to the connecting portion, a link connection to control the position of the body portion, and a locking link to lock the link connection in position.

5. A main frame and a folding frame supported thereby, said folding frame including a pivotally mounted connecting portion, 10 a body portion pivotally attached thereto, an extensible portion also pivotally attached to the connecting portion, a link connection to control the position of the connecting portion, and a locking link pivotally connected 15 to the extensible portion to lock the link connection in position.

6. A main frame including a bracket and a post projecting upwardly therefrom, and a folding frame supported by the main frame, 20 said folding frame including a connecting portion pivotally mounted on said post, a body portion pivotally attached thereto, and an extensible portion also pivotally attached to the connecting portion, link connections 25 pivotally attached to said bracket and to said connecting portion, and a locking link pivotally connected to said link connection and with said extensible portion.

7. A main frame including a bracket and 30 a post rigidly secured thereto, and a folding frame including a connecting portion pivotally attached to the upper end of said post, a body portion pivotally attached to one edge of said connecting portion, and an extensible portion pivotally attached to the 35 opposite edge of said connecting portion, legs pivotally attached to the extensible portion, a leg operating rod, link connections pivotally attached to said bracket and to

said connecting portion, and a locking link 40 pivotally secured to said link connection and to said leg operating rod.

8. A main frame and a folding frame supported thereby, said folding frame including a pivotally mounted connecting portion, a body portion pivotally attached thereto, an extensible portion also pivotally attached to the connecting portion, a link connection to control the position of the body portion, a locking link to lock the link connection in position, and means for insuring locking action of the locking link. 50

9. A main frame and a folding frame supported thereby, said folding frame including a pivotally mounted connecting portion, 55 a body portion pivotally attached thereto, an extensible portion also pivotally attached to the connecting portion, a link connection to control the position of the body portion, and a locking link to lock the link connection in position, said locking link being connected to move independently of the link connection.

10. A main frame and a folding frame supported thereby, said folding frame including a pivotally mounted connecting portion, a body portion pivotally attached thereto, an extensible portion also pivotally attached to the connecting portion, a link connection 65 to control the position of the body portion, a locking link to lock the link connection in position, and means for preventing unintentional unlocking movement of the locking link. 70
